UNITED STATES PATENT OFFICE.

BENEDICT W. SHALLBETTER AND WILLIAM T. ABRAMS, OF MINNEAPOLIS,
MINNESOTA.

INK-FOUNTAIN FOR PRINTING-PRESSES.

1,105,850.

Specification of Letters Patent.

Patented Aug. 4, 1914.

Application filed February 21, 1914. Serial No. 820,189.

To all whom it may concern:

Be it known that we, BENEDICT W. SHALLBETTER and WILLIAM T. ABRAMS, citizens of the United States, residing at Minneapolis, 5 in the county of Hennepin and State of Minnesota, have invented certain new and useful Improvements in Ink-Fountains for Printing-Presses; and we do hereby declare the following to be a full, clear, and exact 10 description of the invention, such as will enable others skilled in the art to which it appertains to make and use the same.

Our invention has for its object to provide an improved ink fountain for printing 15 presses; and, to this end, it consists of the novel devices and combinations of devices hereinafter described and defined in the claims.

Considerable difficulty is experienced with 20 the ink fountains now in general use when it is necessary to change the color of the ink held therein or in giving the same a thorough cleansing. This difficulty arises in the attempt to separate the parts of the ink 25 fountain which are usually thoroughly cemented together by ink that has worked therebetween and dried and in the removal of the unused ink from the ink trough. This separation and cleansing of the parts necessitates a large amount of dirty work and 30 requires the press to stand idle for a considerable length of time. To overcome this difficulty, we provide a feed roller and an ink trough which may be simultaneously 35 and bodily lifted from the casing in which they are mounted, at which time said roller is held in its original position with respect to the ink trough, thereby acting as a stopper to prevent the ink from flowing from the 40 ink trough at the time said ink trough is being removed from the casing and carried to a receptacle provided for holding the ink.

Our invention also provides means whereby the feed roller and ink trough may be very 45 quickly secured in a working position within the casing or removed therefrom.

In the accompanying drawings, which illustrate the invention, like characters indicate like parts throughout the several views.

Referring to the drawings, Figure 1 is a

right side elevation of the improved ink fountain and supporting arm, which connects the same to the frame of the printing press; Fig. 2 is a plan view of the same, removed from its supporting arm; Fig. 3 is a longitudinal vertical section, taken on the irregular line $x^3 x^3$ of Fig. 2; Fig. 4 is a front end elevation of the improved ink fountain, some parts being broken away, 55 and some of the exposed parts being shown in section; and Fig. 5 is a left side elevation of the same.

Of the parts of the printing press illustrated for the purpose of showing the improved ink fountain applied in working position, the numeral 1 indicates the press frame, and the numeral 2 indicates the rotary ink plate or dial.

Referring now in detail to the improved 70 ink fountain, the numeral 3 indicates a horizontally extended rectangular casing, open at its forward end, and hinged near its rear end for vertical swinging movement to a pair of laterally spaced, vertically projecting hinge 75 lugs 4. These hinge lugs 4 project through the bottom of the casing 3, engage the inner vertical faces of the sides of said casing 3, and thereby hold said casing against lateral movement. As shown, the hinge lugs 4 are 80 integral with a plate 5 secured to the outer end of a bracket 6 by a set screw 7. This bracket 6 is secured to the press frame 1 for longitudinal adjustments toward and from the dial 2 by a set screw 8, adapted to be 85 passed through any one of a plurality of longitudinally spaced perforations, not shown, in the bracket 6.

The free or inner end of the casing 3 is held in different vertical adjustments with 90 respect to the dial 2 by a long vertically extended thumb-screw 9, having screw-threaded engagement with the bracket 6, and on which rests the bottom of the casing 3. A lock nut 10 is provided for holding the 95 thumb-screw 9 against rotation in the bracket 6. Obviously, by turning the thumb-screw 9 in the proper direction, the inner end of the casing 3 may be raised, and by turning said screw in a reverse direction, said 100 casing will follow the same under the action of gravity.

The outer upper end portions of the sides of the casing 3 are formed separate from the main portion thereof to afford movable side sections 11. These side sections 11 are 5 hinged to the casing 3, at their inner ends, for vertical swinging movement, by rivets 12. The lower half of a pair of horizontal axially alined bearing seats 13 is formed in the sides of the casing 3, and the coöperating 10 upper half thereof is formed in the lower horizontal edges of the hinged sections 11.

Mounted in the open end of the casing 3, between the sides thereof, is a feed roller 14, keyed to the intermediate portion of a tubular shaft 15, journaled, at its ends, in the 15 seats 13. Integrally formed on one end of this tubular shaft 15, and located on the right side of the casing 3, is a ratchet wheel 16.

20 The hinged sections 11 are locked to the casing 3, which, in turn, secures the tubular shaft 15 in the seats 13, by lever-equipped lock heads 17 and coöperating lock links 18. These lock links each comprise a pair of 25 laterally spaced straps that embrace the hinged sections 11 and underlying portions of the sides of the casing 3. The lower ends of these straps are pivotally secured to the casing 3 by pins 19, and the upper ends 30 brace the lock heads 17, and are eccentrically secured thereto by pivot pins 20. The lock heads 17 are adapted to be moved into and out of seats 21, formed in the upper outer end portions of the hinged sections 35 11, by an oscillatory movement of said heads and a swinging movement of said lock links 18. The hinged sections 11 are further locked to the casing 3 against outward lateral movement by depending lips 11^a, formed 40 thereon and arranged to engage the inner vertical faces of the sides of said casing when said sections are turned down. These lips 11^a also perform another important function that will presently appear. When 45 the lock heads 17 are swung on the lock links 18 into a position, indicated by dotted lines in Fig. 5, the hinged sections 11 may be raised as indicated by dotted lines in Fig. 5, thereby permitting the shaft 15 and 50 attached feed roller 14 to be removed together from the casing 3. This removal of the feed roller 14 and its shaft 15, simultaneously and as an entirety, from the casing 3, is highly important, as will presently appear.

55 Intermittent rotary movement is imparted to the feed roller 14, in the direction of the arrow marked on Fig. 1, by an oscillatory arm 22, having a laterally projecting shaft 23, journaled in and extending completely through the tubular shaft 15. Formed on the outer projecting end of the shaft 23, is an annular groove 24, into 60 which one of the straps of the lock links 18 enters to detachably secure said shaft 65

against removal from the shaft 15. Obviously, by manipulating the levers of the lock head 17, the hinged sections 11 and the shaft 23 may be simultaneously locked in operative positions or released therefrom. 70 Pivotedly mounted on the arm 22, above its shaft 23, is a lock dog 25, which coöperates with the ratchet wheel 16 to rotate the feed roller 14 in the direction of said arrow when the free end of the arm 22 is pulled down, but will slip over said ratchet wheel 75 when said arm moves up. The outer, or free, end of the arm 22 is pulled downward by chain 26, connected to a reciprocating part, not shown, of the printing press. This arm 22 is weighted at 27 to a sufficient extent to return the same to its normal position under the action of gravity. On the casing 3 is a laterally projecting stop 28, which underlies the weighted portion of the arm 22 80 and limits the upward movement of the outer end of said arm.

85 Detachably and removably mounted in the casing 3, is an ink trough 29, with its bottom inclined downward toward the feed 90 roller 14 and so arranged as to deliver ink to said feed roller at a point below its axis. The sides of the ink trough 29 extend parallel with the sides of the casing 3 and they 95 embrace the ends of the feed roller 14, and closely engage the same. The sides of the ink trough 29 extend substantially to the axis of the feed roller 14 and they are notched at their intermediate end portions to afford a clearance for the shaft 15. By 100 reference to Figs. 2 and 4, it will be noted that the sides of the ink trough 29 are spaced a considerable distance from the sides of the casing 3, thereby preventing any of the ink from working into the bearings 105 of the shafts 15 and 23. It will also be noted that the ends of the feed roller 14 are formed with annular channels 30, which further prevent the ink from working from the ink trough into said bearings. The lips 110 11^a, previously referred to, engage the sides of the ink trough 29 and hold the same in engagement with the ends of the feed roller 14.

115 The outer end of the ink trough 29 rests directly on the upper edge of the outer end of the casing 3 and is supported thereby. The ink trough 29 is held against endwise movement in the casing 3 by a depending bifurcated spring 31, formed on the outer 120 end thereof. This spring 31 bears against the outer vertical face of the end of the casing 3, and the prongs thereof embrace a thumb-screw 32, having screw-threaded engagement with said casing, arranged to 125 clamp said spring onto said casing. This spring 31 tends to move the lower end of the bottom of the ink trough 29 axially away from the feed roller 14. Secured to the ink trough 29, just above the spring 31, 130

is a finger piece 33, by which said trough may be lifted to and from the casing 3.

As shown, an adjusting wedge 34 is provided for moving the lower end of the ink trough 29 toward the axis of the feed roller 14, against the tension of the spring 31. This wedge 34 is mounted to slide directly on the bottom of the casing 3, and is held for straight line movement by a pair of screws 35, which work in parallel slots 36 formed in the bottom of said casing. The ink trough 29 rests directly on the upper face of the wedge 34 and is yieldingly held in contact therewith by the spring 31. Endwise sliding movement is imparted to the wedge 34 by a long horizontally extended thumb-screw 37, passed through a perforation in the outer end of the casing 3, and having screw-threaded engagement with said wedge. A collar 38, pinned to the thumb-screw 37, holds the same against endwise movement in the casing 3, but permits free rotary movement thereof. Obviously, by adjusting the wedge 34, the ink trough 29 may be properly positioned with respect to the feed roller 14 to cause just the right amount of ink to pass from the said trough to the feed roller.

By adjusting the bracket 6 on the press frame 1, and the casing 3 on the bracket 6, the feed roller 14 may be positioned so that the form roller will properly engage the same.

From the foregoing description it is evident that by opening the hinged sections 11 in a manner previously described, and loosening the set screw 32 to release the spring 31 from the casing 3, the feed roller 14 and ink trough 29 may be bodily and simultaneously removed from the casing 3. At the time the feed roller 14 and ink trough 29 are removed from the casing 3, said roller is held in its original position with said ink trough, thereby acting as a stopper to close the delivery end of said trough and prevent the flow of ink therefrom. After the feed roller 14 and ink trough 29 are removed from the casing 3, the ink in said trough may be emptied into a receptacle, and said trough then placed in a lye bath for the purpose of cleaning the same. The ink on the feed roller 14 may be readily removed by the use of benzin. When the feed roller 14 is properly cleaned, the same, together with another ink trough, containing a fresh supply of ink, may be placed in the casing 3 and the press again started with only a short delay from the time the first ink trough was removed therefrom. By thus providing each press with two or more ink troughs, different colored inks may be used on the press, with very little delay in making the change, and with very little work, and no dirt.

The above described device, while extremely simple and of comparatively small cost to manufacture, is thought to be highly efficient for the purpose had in view.

What we claim is:—

1. An ink fountain comprising a casing, 70 a feed roller, having tubular trunnions removably journaled in said casing, an ink trough detachably secured within said casing for coöperation with said feed roller, an intermittently rotated shaft journaled in 75 the tubular trunnions of said feed roller and removable therefrom, while said feed roller is seated in said casing, and driving connections between said shaft and feed roller, said feed roller and ink trough arranged to be 80 simultaneously removed from said casing.

2. An ink fountain comprising a casing, 85 a feed roller having tubular trunnions journaled in open seats in said casing, an ink trough detachably secured within said cas- 85 ing for coöperation with said feed roller, means for adjusting said ink trough toward and from said feed roller, an intermittently rotated shaft removably journaled in the tubular trunnions of said feed roller, driv- 90 ing connections between said shaft and feed roller, said feed roller and ink trough ar- 90 ranged to be simultaneously removed from said casing, and means for locking the tubu- 95 lar trunnions of said feed roller in said open 95 seats, and for locking said shaft against endwise removal from said tubular trun- nions.

3. An ink fountain comprising a casing, 100 having hinged side sections, axially alined bearing seats formed in said casing and hinged side sections, a feed roller having a tubular shaft journaled in said seats, an inter- 105 mittently rotated shaft journaled in the tubular shaft of said feed roller, coöperat- 105 ing lock levers and lock links for securing said hinged side sections onto the tubular shaft of said feed roller, and for securing said intermittently rotated shaft against 110 endwise removal from said tubular shaft, and an ink trough arranged to deliver to 110 said feed roller.

4. An ink fountain comprising a casing, 115 a feed roller having tubular trunnions removably journaled in said casing, an ink trough removably mounted within said cas- 115 ing for coöperation with said feed roller, a driven shaft journaled in the tubular trunnions of said feed roller and removable therefrom, while said feed roller is seated in 120 said casing, and driving connections be- 120 tween said shaft and feed roller, said feed roller and ink trough arranged to be simultaneously removed from said casing.

5. An ink fountain comprising a casing hav- 125 ing hinged side sections, axially alined open bearing seats in said casing, a feed roller having tubular trunnions removably jour-

naled in said open seats, a driven shaft removably journaled in the tubular trunnions of said feed roller, driving connections between said shaft and feed roller, coöperating lock levers and lock links, securing said hinged side sections over said open seats for locking the tubular trunnions of said feed roller against removal therefrom, and for securing said shaft against removal from

said tubular trunnions, and an ink trough 10 arranged to deliver to said feed roller.

In testimony whereof we affix our signatures in presence of two witnesses.
